COMBINATION PUNCH AND RIVETER

Gilbert R. Rains, Hutchinson, Kans., assignor to Rains Manufacturing Company, Inc., Newton, Kans., a corporation of Kansas

Filed Apr. 29, 1965, Ser. No. 85,017

Term of patent 14 years

(Cl. D54—10)

FIG. 1.

FIG. 3.

FIG. 2.

FIG. 4.

FIG. 5.

FIG. 7.

FIG. 6.

FIG. 1 is a combination punch and riveter showing my new design;

FIG. 2 is a side elevation thereof;

FIG. 3 is an elevation as seen from the left of FIG. 2;

FIG. 4 is an elevation as seen from the right of FIG. 2;

FIG. 5 is a cross-section taken on line 5—5 of FIG. 2;

FIG. 6 is a cross-section taken on line 6—6 of FIG. 2; and

FIG. 7 is a fragmentary cross-section taken on line 7—7 of FIG. 2.

I claim:

The ornamental design for a combination punch and riveter, as shown and described.
